UNITED STATES PATENT OFFICE

2,515,421

LOCK FOR CABINETS

John H. Page, North Muskegon, Mich., assignor
to The Shaw-Walker Company, Muskegon,
Mich., a corporation of Michigan

Original application October 20, 1945, Serial No.
623,546. Divided and this application October
11, 1947, Serial No. 779,399

8 Claims. (Cl. 292—34)

1

This invention relates to improvements in locking means for fire-resisting cabinets or safes of the kind having a metal shell with an inner liner of molded insulation.

One of the major difficulties in constructing a fire-resisting record container which will protect its contents against damage when the container is subjected to a fire, has been to provide a locking means which will not provide a pathway for the entry of heat into the interior of the cabinet through the metal lock parts.

Another difficulty has been to provide a locking mechanism which does not require a reduction in the thickness of the insulation in the wall of the cabinet to provide space for its installation and operation.

Still another difficulty, and a very serious one, encountered in providing locking means for multiple compartmented, insulated containers has been to provide a locking means actuated by a single lock which does not require an opening connecting one insulated compartment with another.

The main object in providing an insulating partition between the adjoining compartments of a multiple compartmented, fire-resisting container is to protect the contents of each compartment independently of any other compartment.

Should failure of any compartment occur and excessively high temperatures or actual combustion occur in this compartment as a result of said failure, it is important that excessive temperature, gases or flames from the failed compartment be prevented from entering and contributing to the failure of the adjoining compartments.

Heretofore, locking mechanisms for multiple compartmented, insulated record containers which are actuated by a single lock have required a chase or connecting opening between adjoining compartments. In order not to take up room which is needed for filing records, it has been the practice to provide a continuous chase in the insulated walls of the compartments to house a rod which is actuated by a single lock, with this rod actuating locking means in the several compartments.

The reduction in the thickness of the insulation in the walls of the compartments to provide clearance for this lock rod causes a weakening in the walls at this point, and under sudden impact, or because of expansion strains when the cabinet is exposed to sudden high temperatures, cracking may result at this weak point and excessive heat may enter.

Where the lock rod passes through the parti- 55

2

tion separating adjoining compartments or where the aforementioned continuous chase opens into adjoining compartments a means is provided for the passage of gases, etc., which in the event of failure of one compartment, may contribute to the failure of the others.

To eliminate these objections which are inherent in the design of present locking mechanisms for insulated record containers, I have provided a new locking mechanism and method of installing the same along the joint or front opening of the container, without encroaching on the main body of the insulation, as will appear from the following description of one embodiment of my invention.

This application is a division of my prior application, Serial No. 623,546, filed October 20, 1945, and relates more particularly to the construction of the latch housings and locking rod

20 and means for assembling the same in the cabinet.

In the drawings:

Figure 1 is a front view of a two compartment 25 drawer type fire-resisting record container to which the improved locking mechanism is applied.

Figure 2 is a section taken on line 2—2 of Figure 1.

30 Figure 3 is a section taken on line 3—3 of Figure 1, but with the drawers omitted.

Figure 4 is an enlarged detail perspective of one of the temporary fixture parts used for locating the lock housing in the container shell, 35 when the insulation is poured into the latter during manufacture of the cabinet.

Figure 5 is a perspective fragmentary detail of the housings for the lock and latch mechanisms respectively, assembled with the temporary fixture parts used for locating them in the container shell.

40 Figure 6 is a detail perspective view of a latch member, together with a temporary fixture to assist in mounting it in the latch housing.

Figure 7 is an enlarged vertical section taken along the locking tube and transversely of the lock and latch housings, to illustrate the method of inserting the lock tube and its latch operating levers in the cabinet.

50 Figure 8 is a view similar to Figure 7, after the lock tube has been fully inserted in place, and connected to the locking mechanism in the lock housing.

Figure 9 is a detail perspective of the lock.

Figure 10 is a detail section taken through the

drawer jamb and one of the latch housings, and showing the latch in retracted position.

Figure 11 is a view similar to Figure 10, but showing the latch in normal extended position.

Figure 12 is a detail section taken through the drawer jamb and the locking housing, and showing the lock in extended, or unlocked position in the latter.

Figure 13 is a section similar to Figure 12, showing the lock pushed into locking position.

Figure 14 is a section similar to Figure 13, showing a modified form of locking mechanism comprising a concealed device for unlocking the other compartments from a master drawer compartment when the drawer in the latter is opened.

Figure 15 is a section showing another arrangement for a concealed unlocking device operating on the same principle as that shown in Figure 14.

Figure 16 is a detail perspective view of a pusher plate forming part of the latch operating mechanism.

Referring now to details of the embodiment of the invention illustrated in the drawings, 10 indicates a fire-resisting cabinet or safe, having insulated top, bottom, side and rear walls 11, 12, 13 and 14, and an intermediate horizontal partition 15 forming two compartments 16 and 17 each with framed openings at the front of the cabinet. In the form of cabinet illustrated, the two compartments contain sliding drawers 21 and 22, having similar insulated front heads 23. It will be understood that the drawer structure is merely shown for purposes of illustration of my improved locking mechanism which can be applied as well to other closure members such as hinged doors, or a combination of drawers and doors, if desired.

The cabinet walls are formed as usual by a metal casing filled with a suitable insulating liner, molded in the casing, as is usual with cabinets of this kind.

The framed compartment openings 16 and 17 each have the usual stepped side jambs, for receiving similar shaped stepped margins of the drawer heads 23. In the form shown, the framed openings also have outwardly extending flanges 24 interfitting with inwardly extending flanges 24a on the drawer heads.

The locking mechanism includes as its principal elements, a lock 25 and latch devices 26, 27 for the drawers 21 and 22 respectively. The lock is operatively connected with the two latch devices by a locking rod 28. As will be seen in Figures 1, 2 and 3, all of these locking parts are located along one side of the compartment opening jambs, and forwardly of the rear faces of the drawer heads 23, so that they are outside of the main body portion of the insulation liner of the adjacent side wall 13.

The lock 25 is slidably mounted in a lock housing 30 open at its front end and having an integral cylindrical spring chamber 31 projecting from its rear end. The lock is installed in this housing as will hereafter be described.

The latch devices 26 and 27 are similar, each including a generally L-shaped hollow housing 35 having one leg widened longitudinally, with a tapered offset portion 36, and the other leg 37 being generally rectangular in cross section, and open at its end, as shown in Figures 5, 10 and 11. The latch mechanism is installed in this housing as will presently appear.

The lock and latch housings 30 and 35 are held in correct position and alignment in the metal

casing while the installation is poured in the latter, by temporary fixture means, as follows:

A lock housing locating pin 40 (Figure 4) has a tongue 41 which fits in the open end of the lock housing 30. Said tongue is projected through the lock hole 39 provided in the front edge of the cabinet frame, a distance limited by the enlarged portion of said locating pin. The tongue 41 and the housing 30 have registering holes 42, 43 and 44 which are brought into exact alignment by passing a pouring rod 45 therethrough as shown in Figure 5.

The open ends of the latch housing legs 37 are inserted in holes 46, 46 in metal frame members 47 disposed along the sides of the drawer openings, and are held in position while the pouring rod 45 is inserted in close-fitting relation through the holes at opposite ends of the elongated legs 36 of said housings, to close off said holes, as shown in Figure 5. The bottom end of said pouring rod is passed through a threaded aperture 49 in the bottom of the cabinet, said bottom end being provided with a threaded portion 50 engaging in the said aperture by turning the rod handle 51, so that a few turns locks the entire temporary fixture above described in position for the pouring operation.

Forms may then be inserted in the front frame openings of the cabinet and the insulation is poured through a hole in the bottom of the cabinet in the usual manner.

After the insulation is set, the pouring rod 45 is turned to unscrew the threads 50, and the rod may then be withdrawn. The lock housing locating pin 40 is also withdrawn so that the cabinet walls are then complete, with latch housings and lock housing connected by a cylindrical bore ready for installation of the locking mechanism, as will now be described.

For installing the locking mechanism, the cabinet is preferably placed on its back with the end openings up. Each latch member 55 for the two compartments is then assembled with its spring 56 compressed in its hollow body by means of a hook 57 inserted through a hole 58 in the beveled end of said latch member, said spring being held under compression temporarily by an end piece 59 pivoted on the opposite end of said hook, as shown in Figure 6. The latch members are then inserted in legs 37 of the latch housings so that a side opening 60 in the rear end of latch member 55 aligns with the legs 36 of said housings, and with the springs still compressed toward the beveled ends of said latch members.

The locking rod 28 is then installed by inserting it endwise from the bottom of the cabinet along the cylindrical bore left by the pouring rod. Said locking rod consists of a hollow tube, having two latch operating levers 61 and 62 pivotally mounted therein on cross pins 63, and arranged so that their free ends are initially folded inwardly along and within the limits of said tube, but may be swung outwardly through a slotted side opening 64 extending along said tube.

When the locking rod or tube 28 is first inserted in the bore, the slot 64 is turned upwardly as shown in Figure 7, but when the tube is moved within a short distance of its final position, it is rotated 180° so that the latch levers 61 and 62 are in position to fall by gravity into the widened tapered legs 36, 36 of the latch housings, as indicated in dotted lines in Figure 7, the legs 36, 36 being sufficiently elongated longitudinally of the rod 28 to permit this pivoting movement of the levers within the confines of the housings.

When the locking tube is further advanced to its final position, as shown in Figure 8, the ends of the latch levers 61 and 62 move into operative position in the side openings 60 of the latch members 55 and in the rear of the springs 56, which are still held under compression by the hooks 51. The hooks 51 are then removed, so the latch members assume their normal operative position, with the springs 56 engaging the ends of the latch levers 61 and 62. A screw plug 65 is then turned into the threaded hole 49 at the bottom of the cabinet to form a bearing support for the bottom end of the lock rod or tube 28.

The lock is then installed in the lock housing 30 in the following manner: A lock spring 68 is first inserted in the cylindrical chamber 31 at the rear of the housing. A lock tube operating lever 69 is next inserted through the lock opening and fixed on the end of the lock tube, said tube operating lever having an aperture fitting over said tube, with a tongue 70 which interlocks in the slot 64 of said tube, to hold the lever from rotation relative to the latter. An L-shaped pusher plate 71 has one leg 72 engaging the inner end of the lock member 25, and has a stud 73 projecting inwardly to form a seat for the end of the lock spring 68. (See Figures 8 and 12.) The second leg 74 of the pusher plate 71 extends along one side of the lock member 25 and has an angularly arranged cam slot 75 formed therein, for engagement with the out-turned end 76 of the lock tube operating lever 69.

To assemble the lock member 25 and pusher plate, the pusher plate is first pushed inwardly against the lock spring 68 to a position about half way between its front and rear positions. This brings the end 76 of lock operating lever 69 in a central position relative to the lock housing. The parts may be held momentarily in this position by any suitable clamp or hook, engaged with one of the latches, to hold the tube 28 in the same half-way position. The lock member 25 has a slot 78 formed centrally of its inner end, through which the end 76 of the lever 69 can be passed, into the cut-out area 79 at the side of the lock. The clamp or hook may then be disengaged from its latch and the entire locking mechanism is then ready for operation.

The arrangement is such that by sliding the lock member 25 and pusher plate 71 bodily inwardly or outwardly, the lock tube 28 will be rocked on its axis. Thus when the lock member 25 is in extended position shown in Figure 12, the latch levers 61 and 62 will be withdrawn from locking position, as seen in Figure 10, and when the lock member 25 is pushed inwardly, as in Figure 13, the latch levers 61 and 62 will be forced forwardly into locking position, as seen in Figure 11.

It will be observed that outward movement of the lock member 25 relative to the pusher plate 71 is limited by the inner end 76 of the lever 69, both when the lock member is in locked or in unlocked position. Although said lock member can be withdrawn from the housing 35 when the lock member is in intermediate position with the end of the lever 76 in registry with slot 78, it will be understood that the lock member is never idle in this intermediate position so that accidental withdrawal of the lock member is not likely to occur.

The lock member 25 is held in locked position by a laterally movable spring-pressed locking bolt 80, which engages in a locking recess 81 at one side of the lock housing 30. The lock mechanism

for controlling the locking bolt 80 is contained within the locking member and may be of any well-known tumbler type including a tumbler barrel 82, so that details thereof need not be further described herein.

To lock all compartments it is only necessary to push the locking member 25 to the rear of the lock housing 30. When in this position, the bolt 80 of the lock springs into the recess 81 so that the cabinet is locked until unlocked by means of a key.

Thus, the inward movement of the lock 25 acting through the lock spring pusher plate 71 and the lock rod operating lever 69, causes the lock rod 28 with its latch operating levers 61 and 62 to rotate sufficiently to move the latches outward into engaging position with the recesses 85 provided in the side wall of the drawer head. Should any of the drawers be open at the time the cabinet is locked, the action of closing the drawer will cause the latch for that compartment to be forced inward against the compression spring 56 contained within the latch and, upon the drawer reaching its closed position, the latch will spring outward again into the recess 85 in the side wall of the drawer head, thus locking the drawer.

It will be evident that the lock construction just described does not provide a pathway for the conduction of heat to the interior of the cabinet, and that the mechanism requires no space to be taken away from the interior of the cabinet to provide for its installation.

In other words the latch mechanism is wholly contained within the narrowed outer stepped jambs at the sides of the closure openings, and is disposed in one corner of the cabinet outside of the inner surfaces of the insulated drawer heads 22, and the interior dimensions of the cabinet, as defined by the inner surfaces of the insulated side walls and said inner surfaces of said drawer heads.

The beveled outer ends of the sliding latch members 55 fit snugly in the respective detents 55a in the adjacent sides of their respective drawer heads, so that when the drawers are closed and latched the latch housings are sealed off from the drawer compartments.

Thus this construction permits a uniform wall thickness to be maintained around every compartment, and there is no opening from one compartment of the cabinet to any other compartment.

It will be understood the locking mechanism above described may be employed with various auxiliary or combination locking arrangements, where it is desired to provide additional independent locks for one or more compartments, but retaining inter-communicating lock mechanisms between certain, or all of the compartments. For instance, it is often desired to provide one of the drawers with a combination lock which locks said drawer independently of the regular locking mechanism. With such an arrangement, all of the drawers excepting the one having an independent lock are unlocked by the plunger lock 25, and the drawer having the independent lock is unlocked by both locks.

Another permissible variation of the auxiliary locking arrangement described in the preceding paragraph consists in omitting the latch for the drawer having the combination or auxiliary lock. In this case the latter drawer can be unlocked and opened while the remaining drawers are still locked by the regular mechanism.

Still another variation employing an auxiliary locking device is shown in Figure 14. The modified form of latch means shown in this figure is especially designed for use with the drawer 21 disposed adjacent the lock housing 30, but having an auxiliary lock (not shown) independent of the regular locking mechanism. In this case, the regular latches and locking mechanism controlling the locking of the other drawers can be actuated for unlocking the latter by means of a pin 85, which can be inserted through an extended portion 86 communicating with the locking recess 81 of the lock housing 30 only when the adjacent drawer 21 is unlocked and in open position. By inserting the pin 85 into the locking recess, the spring pressed locking bolt is depressed and can be released from recess 81 to unlock the other drawers. The pin 85 can be connected to the inside of the drawer by a chain 87, if desired. With this form of concealed unlocking device, it will be further understood that the key hole and tumbler barrel (not shown) of the sliding lock member 25 can be omitted, if desired, and the regular locking mechanism can be locked when desired merely by pushing the lock member 25 inwardly to engage bolt 80 in its locking recess 81.

Figure 15 shows another variation of the concealed unlocking mechanism shown in Figure 15. In Figure 15, a sliding block 88 is permanently mounted in the hollow extension 86 of the lock housing, and has a push rod or pin 89 connected thereto and extending through the aperture 85a in the extension 86, with its outer end in position to be engaged by the finger when it is desired to unlock the bolt from the interior of the adjacent drawer opening. With this form, the adjacent side of the drawer head has a slotted recess 90 to provide clearance for the pin 89 when the drawer is in closed position.

To facilitate assembly of the unlocking block 88 and pin 89 in the extension 86 of the lock housing, said block has a bore formed in its outer face. The inner end of the pin 89 can be passed through the aperture 85a and inserted in the block 88 with a press fit.

Although I have shown and described certain embodiments of my invention, it will be understood that I do not wish to be limited to the exact construction shown and described, but that various changes and modifications may be made without departing from the spirit and scope of the invention as defined in the appended claims.

I claim:

1. In a locking mechanism, a latch housing having a sliding latch therein, a rotatable control rod adapted for insertion endwise in said housing and a control lever for reciprocal operation of said latch pivotally mounted on said rod so as to be folded lengthwise of the latter for initial insertion in said latch housing, and said housing being elongated longitudinally of said rod to permit the free end of said lever to be thereafter swung laterally of said rod into operative position relative to said latch member.

2. In a locking mechanism, a plurality of latch housings with sliding latches therein, each of said housings having aligned openings offset from said latches, a rotatable control rod, said rod having a plurality of control levers for reciprocal operation of said latches pivotally mounted on said rod so as to be foldable along said rod when the latter is inserted in the openings in said housings, and said housings being elongated longitudinally of said rod to permit the free end of said

levers to be thereafter swung laterally of said rod into operative position relative to the latches.

3. In a locking mechanism, a lock housing open at one end, a lock member slidably mounted in said housing and having a bolt at one side for locking engagement with a detent in said housing, latch means remote from said lock housing, a rockable control rod for said latch means having one end extending into one side of said housing and having a lever fixed thereon, and cam means movable with said sliding lock member engageable by said lever for effecting rocking movement of said control rod by sliding movement of said lock member.

4. In a locking mechanism, a lock housing open at one end, a lock member slidably mounted in said housing and having a bolt at one side for locking engagement with a detent in said housing, latch means remote from said lock housing, a rockable control rod for said latch means having one end extending into one side of said housing and having a lever fixed thereon, and cam means movable with said sliding lock member engageable by said lever for effecting rocking movement of said control rod by sliding movement of said lock member, said locking member having a transverse lip adjacent its inner end for engaging the end of said lever and normally retaining said lock member in its housing, said lip being cut away at an intermediate point to permit bodily insertion of said lock member in the open end of said housing for initial assembly with said cam means, when the control rod and lever are temporarily held at an intermediate point between their fully locked and fully unlocked positions, as and for the purpose described.

5. In a locking mechanism, a latch housing having aligned openings in opposite walls thereof, a rotatable control rod normally extending through and journaled in said openings, a latch member slidably mounted in said housing at one side and transversely of said control rod and having one end extending through another opening in said housing for engagement with a detent, and a control lever for reciprocal operation of said latch member pivotally mounted at one end to said rod and foldable lengthwise of the latter so as to permit initial insertion of the rod and lever through one of said aligned openings, and said housing being elongated longitudinally of said rod to permit the free end of said lever to be thereafter swung away from said rod into operative engagement with said sliding latch member.

6. In a locking mechanism, a latch housing having aligned openings in opposite walls thereof, a rotatable control rod normally extending through said openings and in bearing engagement in the latter, a latch member slidably mounted in said housing at one side and transversely of said control rod and having one end extending through another opening in said housing for engagement with a detent, and a control lever for reciprocal operation of said latch member pivotally mounted at one end to said rod and foldable lengthwise and within the circumference of the latter so as to permit initial insertion of the rod and lever through one of said aligned openings, and said housing being elongated longitudinally of said rod to permit the free end of said lever to be thereafter swung away from said rod into operative engagement with said sliding latch member.

7. In a locking mechanism, an elongated latch housing having aligned openings in opposite end

walls thereof, a rotatable control rod normally extending in bearing engagement through said openings, a latch member slidably mounted in said housing at one side and transversely of said control rod and having one end extending through said housing for engagement with a detent, and a control lever for reciprocable operation of said latch member pivotally mounted at one end to said rod and foldable lengthwise and within the bearing circumference of the latter so as to permit initial insertion of the rod and lever through one of said aligned openings, said housing being elongated interiorly between the end openings thereof and toward said latch member to permit the free end of said lever to be thereafter swung away from said rod into operative engagement with said latch member.

8. A locking mechanism in accordance with claim 7, wherein the latch member is arranged near one end of said housing so that said control

lever may be swung laterally into operative engagement therewith during longitudinal sliding movement of said control rod to its final bearing position in said housing.
